UNITED STATES PATENT OFFICE.

WALTER H. HARRISON, OF NEW EDINBURG, ARKANSAS.

COLLAR FOR ANIMALS.

SPECIFICATION forming part of Letters Patent No. 424,197, dated March 25, 1890.

Application filed June 14, 1889. Serial No. 314,191. (No model.)

To all whom it may concern:

Be it known that I, WALTER H. HARRISON, a citizen of the United States, residing at New Edinburg, in the county of Cleveland and State of Arkansas, have invented a new and useful Collar for Animals, of which the following is a specification.

The invention relates to improvements in collars for animals.

10 The object of the present invention is to provide a bell-collar of simple and inexpensive construction which shall be strong and durable and capable of ready adjustment to fit the necks of various-sized animals.

15 The invention consists in the construction and novel combination and arrangement of parts hereinafter fully described, illustrated in the accompanying drawings, and pointed out in the claim hereto appended.

20 In the drawings, Figure 1 is a perspective view of a collar constructed in accordance with this invention. Fig. 2 is a similar view, the parts being separated; and Fig. 3 is a central longitudinal sectional view.

25 Referring to the accompanying drawings, A designates a bell-collar constructed of sheet metal and composed of two sections A' and A², which are adjustable on each other, whereby the collar may be increased and diminished 30 in size to adapt it to different sized necks.

The upper section A is provided upon each side with a series of adjusting-holes a, which are designed to be engaged by pins b, situated near the end of springs that are riveted or 35 similarly secured to the section A². The upper ends of the section A² are provided with lateral flanges a', which are bent over upon the outer face of the section to form grooves or ways in which the upper section A' slides,

and the said ends are provided with perforations a², which are situated opposite the pins b, that are passed through the perforations a² in securing the parts together. To adjust the collar the ends of the upper section are slipped into the grooves or ways a', and one 45 of the adjusting-holes a on each side of the section A' is made to register with the perforations a², and then the pins b are pushed through the registering-openings and the section pulled slightly apart to bring the neck 50 of the pin in the narrow portion or slot of the hole a, thereby securely holding the parts in place; but when it is desired to readjust the parts it is only necessary to slip the parts together and make the openings register and 55 the springs B will cause the pin to be withdrawn.

From the foregoing description and the accompanying drawings, the construction, operation, and advantages of the invention will 60 readily be understood.

What I claim is—

A bell-collar consisting of the section A' having the series of adjusting-holes and communicating slots, and the section A², having 65 lateral flanges a', forming grooves or ways, and perforations a², and provided with the springs B, having the pins b, having heads to engage said slots, substantially as and for the purpose set forth.

In testimony that I claim the foregoing as my own I have hereto affixed my signature in presence of two witnesses.

WALTER H. HARRISON.
